[57] CLAIM

The ornamental design for a combined medical tool holder and flashlight, as shown and described.

DESCRIPTION

FIG. 1 is a perspective view of a combined medical tool holder and flashlight, showing my new design, with the cover attached;

FIG. 2 is a perspective view thereof, with the cover removed;

FIG. 3 is a top plan view thereof, with cover attached;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a second perspective view, partially broken away and with the cover removed, of the combined medical tool holder and flashlight of FIG. 1; and,

FIG. 10 is a cross-sectional view thereof taken along line x—x in FIG. 3.
